US0D1028949S

(12) **United States Design Patent** (10) **Patent No.:** **US D1,028,949 S**
(45) **Date of Patent:** **** May 28, 2024**

(54) **SYSTEM CONTROL UNIT**

(71) Applicant: **3M Innovative Properties Company**,
St. Paul, MN (US)

(72) Inventors: **William P. Atwood**, St. Paul, MN (US);
Yi-chi Huang, Montréal (CA); **Jeffrey L. Hamer**, St. Paul, MN (US); **Paul D. Henry**, St. Paul, MN (US)

(73) Assignee: **3M Innovative Properties Company**,
St. Paul, MN (US)

(**) Term: **15 Years**

(21) Appl. No.: **29/916,999**

(22) Filed: **Nov. 16, 2023**

Related U.S. Application Data

(62) Division of application No. 29/872,020, filed on Mar. 3, 2023, now Pat. No. Des. 1,011,321, which is a division of application No. 29/758,483, filed on Nov. 16, 2020, now Pat. No. Des. 983,174.

(57) **CLAIM**

The ornamental design for a system control unit, as shown and described.

DESCRIPTION

FIG. 1 is a right top perspective view of a system control unit showing the new design;

FIG. 2 is a front elevation view thereof;

FIG. 3 is a rear elevation view thereof;

FIG. 4 is a left side elevation view thereof;

FIG. 5 is a right side elevation view thereof;

FIG. 6 is a top plan view thereof; and,

FIG. 7 is a bottom plan view thereof.

(Continued)

The dash-dash broken lines in the figures represent unclaimed subject matter and form no part of the claimed design.

1 Claim, 6 Drawing Sheets
